Primary Examiner — Omeed Agilee

(57) **CLAIM**

The ornamental design for a fluid transfer device, as shown and described.

DESCRIPTION

FIG. 1 is a top, front, right-side, perspective view of a first embodiment of a fluid transfer device, showing my new design;

FIG. 2 is a bottom, rear, left-side, perspective view of the fluid transfer device shown in FIG. 1;

FIG. 3 is a front elevation view of the fluid transfer device shown in FIG. 1;

FIG. 4 is a rear elevation view of the fluid transfer device shown in FIG. 1;

FIG. 5 is a left side elevation view of the fluid transfer device shown in FIG. 1;

FIG. 6 is a right side elevation view of the fluid transfer device shown in FIG. 1;

FIG. 7 is a top plan view of the fluid transfer device shown in FIG. 1;

FIG. 8 is a bottom plan view of the fluid transfer device shown in FIG. 1;

FIG. 9 is another front elevation view of the fluid transfer device shown in FIG. 1 showing the fluid transfer device in a first in-use configuration and with environment;

FIG. 10 is another front elevation view of the fluid transfer device shown in FIG. 1 showing the fluid transfer device in a second in-use configuration and with environment; and, FIG. 11 is another front elevation view of the fluid transfer device shown in FIG. 1, shown at a reduced scale, showing the fluid transfer device in a third in-use configuration and with environment.

The broken lines in FIGS. 1-8 depict portions of the fluid transfer device that form no part of the claimed design. The additional broken lines in FIGS. 9-11 depict environmental subject matter and form no part of the claimed design.

1 Claim, 7 Drawing Sheets
